Primary Examiner — Jeffrey D Asch*Assistant Examiner* — Rebekah A Caruso(74) Attorney, Agent, or Firm — Knobbe, Martens, Olson & Bear LLP(57) CLAIM

The ornamental design for a video game controller, as shown and described.

DESCRIPTION

FIG. 1 is a top perspective view of a video game controller embodying my new design, according to one embodiment; FIG. 2 is a bottom perspective view thereof; FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines illustrate portions of the video game controller that form no part of the claimed design.
